ROTARY MOTION TRANSLATING DEVICE

Arthur B. Poole, Bristol, Conn., assignor to The
E. Ingraham Company, Bristol, Conn., a cor-
poration of Connecticut

Application June 27, 1938, Serial No. 216,177

6 Claims. (Cl. 74—112)

This invention relates to an improved rotary motion translating device of the character wherein a substantially continuous rotary motion may be translated into an intermittent or step-by-step rotary motion. The devices of the present invention are primarily designed for effecting the periodic actuation of an electric-switch device, though also available for other uses.

One of the objects of the present invention is to provide a superior rotary motion translating device by means of which a relatively-slow substantially-continuous rotary motion of a driving-member may be translated or converted into a relatively-rapid step-by-step motion.

Another object of the present invention is to provide a superior device of the character referred to which is reliable in operation and not subject to derangement under operating conditions.

A further object is to provide a superior rotary motion translating device characterized by fewness of parts and low cost for manufacture.

A still further object is to provide a superior rotary motion translating device wherein spring-means is interposed between a substantially-continuously-moving driving-member and a normally-intermittently-moving driven-member, and wherein provision is made for effecting the substantially-continuous movement of the said driven-member in the event of the breakage or other failure of the said spring-means.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a view in front elevation of a rotary motion translating device constructed in accordance with the present invention and showing a portion of the front-plate broken away for clarity of illustration;

Fig. 2 is a view mainly in vertical central section on the line 2—2 of Fig. 1 and partly in edge elevation;

Fig. 3 is a broken sectional view taken on the line 3—3 of Fig. 2 and illustrating the positions which the parts assume immediately after the completion of one of the step-by-step turning movements of the stop-arm and its associated parts;

Fig. 4 is a view similar to Fig. 3 but showing the position which the parts occupy an instant

before the unlatching action takes place to release the stop-arm and associated parts for one of its step-movements;

Fig. 5 is a perspective view of the unit comprising the stop-arm, latch-sector, latching-stud 5 and intermittent-drive shaft;

Fig. 6 is a view mainly in front elevation of another form of rotary motion translating device embodying the present invention, and showing a portion of the front-plate broken away for 10 the purpose of clarity of illustration;

Fig. 7 is a bottom-edge view thereof;

Fig. 8 is a broken-detail sectional view taken on the line 8—8 of Fig. 6; and

Fig. 9 is a perspective view of the unit comprising the stop-arm and the intermittent-drive shaft of the device of Figs. 6, 7 and 8.

The particular rotary motion translating device chosen for illustration of the present invention in Figs. 1 to 5 inclusive, includes a front-plate 10 and a complementary back-plate 11 held in spaced relationship parallel with each other by four (more or less) pillars 12. Secured against the rear face of the back-plate 11 is a synchronous electric motor-structure designated by the reference character 13 and requiring no detailed description herein other than to point out that as shown, it is provided with a power-output shaft 14 and leads 15 and 16 which are adapted to be connected to any suitable source of alternating current in the usual manner of synchronous electric motors. The said synchronous electric motor-structure 13 imparts an accurately-timed rotational movement to the power-output shaft 14 and, therefore, serves in effect as timing-means which obviously may be replaced if desired by an ordinary spring-operated time-movement or any other suitable time-mechanism.

Rigidly mounted upon the forward portion of the power-output shaft 14 of the motor-structure 13 is a driving-pinion 17 which meshes into and drives a gear-wheel 18. The gear-wheel 18, just referred to, is staked or otherwise rigidly attached to the hub 19 of a sector-actuating pinion 20, as is especially well shown in Fig. 2. The 45 said sector-actuating pinion 20, together with its hub 19 and the gear-wheel 18 carried thereby, is mounted with freedom for relative rotation upon an intermittent-drive shaft 21, which latter bears at its front end in the front-plate 10 and bears at its rear end in the back-plate 11 with capacity for rotation.

Rigidly mounted upon the intermittent-drive shaft 21 immediately forwardly of the back-plate 11 is the hub 22 of a stop-arm 23 which latter 55

is rigidly staked or otherwise secured to the said hub 22, so that the said parts 22 and 23 constitute a rigid unit with the intermittent-drive shaft 21.

5 For the purpose of resiliently or elastically coupling the intermittent-drive shaft 21 with the gear-wheel 18 and hence with the driving-pinion 17, a chain of parts will be presently described which enables the said gear-wheel 18 to rotate 10 constantly and effect the intermittent turning movement of the said shaft 21.

For the purpose just above referred to, the hub 19 of the pinion 20 has rigidly attached to it a collar 24 which in effect thus becomes a unit 15 with the gear-wheel 18. The said collar 24 is provided with a radially-extending pin 25 with which is coupled the inner convolution of a spiral transmitting-spring 26 which has its opposite end or outer convolution secured to a stud 27 20 riveted to the end-wall of a cup-shaped spring-barrel 28. The spring-barrel 28, just referred to, is staked or otherwise rigidly secured to the rear end of an intermittent-drive pinion 29 rigidly mounted upon the intermittent-drive shaft 25 21 so as to drive the same. The pinion 29 meshes into and drives an intermittent-drive wheel 30 rigidly mounted upon an intermittently-driven control-shaft 31 journaled at its rear end in the back-plate 11 and intermediate its respective 20 opposite ends journaled in the front-plate 10 through which it forwardly projects.

Rigidly attached to the projecting forward end of the control-shaft 31, just above referred to, is a control-wheel or member 32 preferably formed 35 of insulating material throughout, so as to guard against the access of electrical current to the control-shaft 31 and the parts in electrical connection therewith.

The control-wheel or member 32, just above referred to, is adapted to have imparted to it step-by-step rotational movement in the direction indicated by the arrow in Fig. 1, and as the parts shown are proportioned, each step-by-step movement of the said control-wheel 32 will be 45 substantially 45° or one-eighth revolution for each step.

The said control-wheel 32 is provided upon its periphery with three (more or less) cam-lugs respectively numbered 33, 34 and 35, spaced from 50 each other by an equal number of clearance-notches respectively numbered 36, 37 and 38. Each of the cam-lugs 33, 34 and 35 is adapted to sequentially coat with an inclined cam-finger 39 formed at the outer end of a resilient contact-arm 55 40. The said contact-arm 40 is secured by means of suitable screws 41—41 to an insulating-block 42 which in turn is secured to the forward face of the front-plate 10 in any suitable manner, such, for instance, as by means of screws 43—43. 60 About midway of its length, the resilient contact-arm 40 carries a movable contact 44 which is adapted to periodically engage with a similarly-shaped stationary contact 45 carried at the inner end of a relatively-rigid contact-bracket 46 secured to the insulating-block 42 by means of screws 47—47. Respectively clamped against the outer end of the contact-arm 40 and the outer end of the contact-bracket 46, by their respective outer screws 41 and 47, are lead-wires 48 and 49 65 which extend to a device which it is desired to electrically control. The device to be controlled may, of course, assume a wide variety of forms and is not per se involved in the present invention, but by way of illustration, it may be con-

sidered to be an automatic washing machine or the like.

Returning now to the stop-arm 23, it will be noted that the outer end thereof is provided with a bushing 50 in which is mounted for rotation a 5 latching-stud 51 having a semi-cylindrical latching-head 52 which projects rearwardly beyond the rear face of the said stop-arm into position to releasably engage a latching-abutment 53, constituting the head-portion of an abutment-stud 54 riveted in the back-plate 11 and having the said latching-abutment 53 extending forwardly from the said back-plate 11.

The reduced forward end of the latching-stud 51 projects beyond the bushing 50 and has staked or 15 otherwise secured to it a latch-sector 55 having peripheral gear-teeth 56 arranged concentrically with the latching-stud 51 and meshing with the sector-actuating pinion 20 before referred to.

For the purpose of making clear the operation 20 of the device illustrated in Figs. 1 to 5 inclusive, let it be assumed that the parts are in the positions in which they are illustrated in Figs. 1 to 3 inclusive, and that a supply of alternating current is connected to the leads 15 and 16 of the 25 synchronous electric motor-structure. Under the conditions just referred to, the driving-pinion 17 will effect the continuous rotation of the gear-wheel 18 and the parts rigidly connected thereto, so that the spiral transmitting-spring 26 will be 30 placed under tension, with the effect of urging the stop-arm 23 to turn in a clockwise direction as viewed in Figs. 3 and 4. The said stop-arm 23, however, will be prevented from turning in the manner just referred to by the engagement of 35 the semi-cylindrical latching-head 52 of the latching-stud 51 with the latching-abutment 53 of the abutment-stud 54.

As the gear-wheel 18 continues to turn and thus effects the further tensioning of the transmitting-spring 26 and the clockwise rotation of the sector-actuating pinion 20, the latch-sector 55 will be turned in a counterclockwise direction with reference to the stop-arm 23 by which it is carried, and thus effect the similar counterclockwise turning of the semi-cylindrical latching-head 52. Ultimately, the transmitting-spring 26 will have been tensioned substantially to its maximum tension and the corner 57 of the said latching-head will come into registration 50 with the lower inner corner of the latching-abutment 53, as is shown in Fig. 4.

The slight further counterclockwise turning movement of the latch-sector 55 and hence of the latching-head 52 will clear the corner 57 55 of the said latching-head from the latching-abutment 53, whereupon the transmitting-spring 26 will act to rapidly swing or snap the stop-arm 23 and the parts carried thereby one full turn in a clockwise direction.

During the rapid swinging movement of the stop-arm 23 and associated parts, as just above referred to, the latch-sector 55 (while also bodily moving) will be turned in a clockwise direction by the engagement of its teeth 56 with the sector-actuating pinion 20, so that by the time that the said stop-arm has completed one turn, the latching-head 52 will have also been turned in a clockwise direction, so that it assumes the position illustrated in Fig. 3, to thereby engage the 70 latching-abutment 53 and thus check the turning movement of the stop-arm 23 and the parts carried thereby. The parts will now have resumed the positions in which they are shown in Fig. 3.

When the stop-arm 23 snaps around in a clockwise direction as described above, under the tension of the transmitting-spring 26, the intermittent-drive shaft 21 coupled to the said stop-arm 5 will also have imparted to it one complete revolution, with the result that the intermittent-drive pinion 29, also rigidly attached to the said shaft 21, will effect a one-eighth turn of the intermittent-drive wheel 30 and hence similarly turn the control-shaft 31 and the control-wheel or member 32. The one-eighth turn thus imparted to the control-wheel 32 will serve to cause the cam-lug 35 to ride out of engagement with the cam-finger 39 of the contact-arm 40, and will bring 10 the clearance-notch 38 into registration with the said cam-finger 39. This movement of the control-wheel 32 will thus permit the resilient contact-arm 40 to swing upwardly and bring its contact 44 into engagement with the stationary contact 45 and thus complete an electrical circuit between the two lead-wires 48 and 49 and so effect the actuation of such electrical device as may be connected to the said lead-wires 48 and 49.

25 The cycle of operation above referred to will be periodically repeated with the result that the control-wheel or member 32 will have successive step-by-step turning movements imparted to it, to thus, at desired intervals, effect the opening and closing of the contacts 44 and 45. The number of cam-lugs or their equivalents upon the control-wheel 32 will be in accord with the action which it is desired to have the said control-wheel effect. In the particular instance shown, the cam-lug 35 of the control-wheel 32 is of such extent as to require two successive step-by-step movements of the said control-wheel in order to cause it to ride clear of the contact-finger 39. Similarly, the clearance-notch 36 in the instance shown is of such extent as to permit the cam-finger 39 to remain therein during two successive step-by-step movements of the control-wheel 32.

It will be seen from the foregoing that the 45 constant rotation of the driving-pinion 17 will be converted into a series of very rapid step-by-step movements of the control-wheel or its equivalent. Thus, the opening and closing of the contacts 44 and 45, or their equivalents, is effected so rapidly as to minimize sparking and other objectionable action.

One of the important features of the present invention is the construction and arrangement of parts whereby in the event of the breakage 55 or other failure of the transmitting-spring 26, the successive openings and closings of the contacts 44 and 45 or their equivalents, will continue to take place, though not with the desired rapidity before referred to. For the purpose just referred to, the gear-teeth 56 of the latch-sector 55 terminate short of one edge of the said latch-sector, so as to leave thereon a driving-abutment 58. The said driving-abutment 58 is adapted, upon failure of the transmitting-spring 60 26, to jam against the teeth of the sector-actuating pinion 20, so as to effect a positive drive connection between the said pinion and the stop-arm 23, and hence with the control-wheel 32.

It will be noted by reference to Fig. 4 in 70 particular that the driving-abutment 58 of the latch-sector 55 is so located that it does not engage with the teeth of the pinion 20 until after the corner 57 of the latching-head 52 has been swung clear of the latching-head 52, and only 75 then in the event that the transmitting-spring 26

fails to function. As before explained, the instant that the corner 57 clears the latching-head 52, the transmitting-spring 26 will, under ordinary conditions, rapidly snap the stop-arm 23 around one revolution, so that the said driving-abutment 58 does not, under ordinary conditions, function at all. In the event, however, that the transmitting-spring 26 or its equivalent is broken or otherwise rendered inoperative, the driving-abutment 58 will be brought into jamming engagement with the teeth of the pinion 20 and thereafter the said pinion 20 will operate to slowly but positively turn the said stop-arm 23 through the intermediary of the latch-sector 55, with the result that the control-wheel 32 will be continuously driven, rather than be driven in step-by-step movement as is the case under ordinary operating conditions.

Coming now to the structure shown in Figs. 6 to 9 inclusive, it may be first explained that the said structure functions to produce the rapid step-by-step rotation of a suitable control-wheel in the same general manner as has been pointed out in connection with the device of Figs. 1 to 5 inclusive.

The rotary-motion translating-device of Figs. 6, 7, 8 and 9, includes a front-plate 59 and a back-plate 60 which are held in spaced relationship with respect to each other by a suitable number of pillars 61. Fastened to the rear face of the back-plate 60 is a motor-structure 62 preferably of the synchronous type and having the usual two complementary leads 63 and 64 for connection to a source of alternating current of commercial frequency.

The said motor-structure 62, above referred to, is provided with a power-output shaft 65 carrying a driving-pinion 66 which meshes into and drives a gear-wheel 67. The gear-wheel 67, just referred to, is rigidly secured to a hub 68 mounted with freedom for relative rotation upon an intermittent-drive shaft 69. The hub 68, just referred to, rigidly mounts a collar 68a provided with a pin 70 to which is attached the inner convolution of a spiral transmitting-spring 71 which has its outer convolution coupled by means of a stud 72 to a cup-shaped spring-barrel 73.

The spring-barrel 73 is rigidly mounted upon an intermittent-drive pinion 74 which in turn 50 is staked or otherwise secured to the intermittent-drive shaft 69 and which meshes into and drives an intermittent-drive gear-wheel 75. The gear-wheel 75, just referred to, is rigidly mounted upon a control-shaft 76 bearing in the front-plate 59 and the back-plate 60 and projecting forwardly beyond the said front-plate 59 where it is provided with a control-wheel or member 77 formed of insulating material. The control-wheel 77 is provided upon its periphery with 55 three (more or less) cam-lugs 78, 79 and 80 and a similar number of clearance-notches 81, 82 and 83.

The cam-lugs 78, 79 and 80 and the clearance-notches 81, 82 and 83 of the control-wheel 77 65 alternately raise and free a sloping cam-finger 84 formed at the free end of a flexible contact-arm 85 which is secured at its opposite end, by means of screws 86—86, to an insulating-block 87. The said insulating-block 87 is secured to 70 the forward face of the front-plate 59 by any suitable means, such, for instance, as rivets 88—88.

About midway of its length, the flexible contact-arm 85 is provided with a movable contact 75

89 which is adapted to engage and disengage a stationary contact 90 mounted upon the inner end of a contact-bracket 91 which is secured at its outer end to the insulating-block 87 by 5 any suitable means such as screws 92-92. Connected to the contact-arm 85 and the contact-bracket 91, by means of one of their respective screws 86 and 92, are lead-wires 93 and 94 respectively, leading to the device to be controlled.

10 Also rigidly attached to the intermittent-drive shaft 69 near the end thereof opposite the pinion 74, is a stop-arm 95 formed at its extreme outer end with a latching-nose 96 and having a forwardly-projecting stop-pin 97. The stop-pin 97, just referred to, is adapted to engage with a latch-actuating finger 98 formed integral with and projecting rearwardly from the gear-wheel 67. The outer edge of said finger 98 is adapted to engage with the sloping face of a cam-block 20 99 projecting from the upper face of a latching-arm 100 for the purpose of disengaging a latching-finger 101 on the said arm, from the latching-nose 96 of the stop-arm 95, in a manner as will hereinafter appear. As shown, the latching-arm 25 100 is secured to the forward face of the back-plate 60 by rivets 102-102.

The device of Figs. 6 to 9 inclusive functions in substantially the same manner as the device of the preceding figures inasmuch as provision is made for converting the substantially-constant and relatively-slow rotary movement supplied by the motor-structure 62 into a relatively-rapid step-by-step movement of the control-wheel 71 or its equivalent. Furthermore, as will herein-after appear, in the event of the failure of the transmitting-spring 71, the said control-wheel will not cease to function, but will be positively propelled continuously rather than in a step-by-step movement.

40 To make clear the operation of the device of Figs. 6 to 9 inclusive, let it be assumed that the parts are in the positions in which they are best illustrated in Fig. 6, in which it will be noted that the latch-actuating finger 98 is in the act of forcing the flexible latching-arm 100 downwardly, so as to disengage its latching-finger 101 from the latching-nose 96 of the stop-arm 95. The instant that the latching-finger 101 is disengaged from the latching-nose 96, as just referred to, by the 45 continuous rotation of the gear-wheel 67, the said stop-arm 95 will snap around substantially one complete revolution in a clockwise direction as viewed in Fig. 6, until its stop-pin 97 engages with the right-hand face of the latch-actuating finger 98.

The snap-rotation of the stop-arm 95, as just above described, will similarly rotate the intermittent-drive shaft 69 and also the intermittent-drive pinion 74 secured thereto. The pinion 74 50 will in turn effect the partial rotation of the intermittent-drive wheel 75 and hence the control-shaft 76 and the control-wheel 77, substantially one-eighth turn. This movement of the control-wheel 77 will cause the cam-lug 78 to ride 55 out of engagement with the cam-finger 84 of the contact-arm 85 and bring the clearance-notch 81 in registration therewith, thus permitting the movable contact 89 to engage with the stationary contact 90 to close the circuit between the two lead-wires 93 and 94.

70 Shortly after the latch-actuating finger 98 has downwardly flexed the latching-arm 100 sufficiently to permit the stop-arm 95 to snap around, so to speak, substantially one revolution, the said latch-actuating finger 98 will pass over the cam-

block 99, whereupon the latter will snap upwardly into a position adjacent the right-hand face of the said latching-arm 100. In this manner, the latching-finger 101 of the said latching-arm 100 will again be interposed in the path of movement of the latching-nose 96 of the said stop-arm 95, which latter is being at this time retarded by the engagement of its stop-pin 97 with the finger 98 of the constantly-rotating gear-wheel 67. Very shortly after the action just mentioned has 10 taken place, the latching-nose 96 of the stop-arm 95 will reengage with the latching-finger 101 on the latching-arm 100 as the said arm 95 is permitted to slowly turn a short distance in a clockwise direction, as viewed in Fig. 6, by the 15 slow continuous movement of the gear-wheel 67 against the finger 98 of which latter the stop-pin 97 is held by the tension of the transmitting-spring 71.

20 As soon as the turning movement of the stop-arm 95 is halted by the reengagement of the latching-nose 96 with the latching-finger 101 of the latching-arm 100, the latch-actuating finger 98 of the gear-wheel 67 will slowly ride away from the stop-pin 97 and ultimately will return to the position in which it is shown in Fig. 6 in readiness for again depressing the latching-arm 100 through the intermediary of the cam-block 99 to thereby permit the next step-by-step movement of the said stop-arm 95 and hence of the control-wheel 71.

25 In the event that for any reason the transmitting-spring 71 should break or otherwise fail to function, the left-hand face of the latch-actuating finger 98 of the gear-wheel 67 will engage with the stop-pin 97 and slowly but positively turn the stop-arm 95 and effect a similar movement of the control-wheel 71.

30 From the foregoing, it will be seen that in both of the forms of the present invention herein shown for illustration, not only is provision made for translating a relatively-slow substantially-continuous movement into a relatively-rapid step-by-step movement, but provision is also made whereby in the event of the failure of the transmitting-springs or their equivalents, the device will not fail to function, but will automatically resort to effecting the slow but positive movement of the respective control-wheels.

35 The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

40 I claim:

1. A rotary-motion translating-device, including in combination: a substantially-constantly-rotating driving-member; an intermittently-rotating driven-member; resilient coupling-means operatively interconnecting the said driving-member with the said driven-member for effecting the movement of the latter by the former; a stop-abutment; a rotary latch-member releasably engageable with the said stop-abutment; latch-releasing means operatively connected with both the said driving-member and the said rotary latch-member for turning the latter out of engagement with the said stop-abutment to release the said driven-member for rapid movement by the said resilient coupling-means; and automatic positive-coupling means 45 50 55 60 65 70 75 80 85 90 95 100 105 110 115 120 125 130 135 140 145 acting to cause the said driving-member to positively drive the said driven-member when the said resilient coupling-means fails to function.

2. A rotary-motion translating-device, including in combination: a substantially-constantly-rotating driving-member; an intermittently-rotating driven-member; a spiral energy-storing coupling-spring operatively interconnecting the said driving-member with the said driven-member for moving the latter; a stop-abutment; a rotary latch-member releasably engageable with the said stop-abutment; latch-releasing means operatively connected with both the said driving-member and the said rotary latch-member for turning the latter out of engagement with the said stop-abutment to release the said driven-member for rapid movement by the said spiral energy-storing coupling-spring; and automatic positive-coupling means acting to cause the said driving-member to positively drive the said driven-member when the said spiral energy-storing coupling-spring fails to function.

3. A rotary-motion translating-device, including in combination: a substantially-constantly-rotating driving-train including a toothed member; an intermittently-rotating driven-member; resilient coupling-means operatively interconnecting the said driving-train with the said driven-member for effecting the movement of the latter by the former; a stop-abutment; a toothed sector pivotally carried by the said intermittently-rotating driven-member and engaged with the teeth of the toothed member of the said driving-train; a latch-member carried by the said driven-member and operatively connected to the said toothed sector for being moved thereby out of engagement with the said stop-abutment to release the said driven-member for rapid movement by the said resilient coupling-means; and automatic positive-coupling means acting to cause the said toothed member of the said driving-train to positively drive the said driven-member when the said resilient coupling-means fails to function.

4. A rotary-motion translating-device, including in combination: a substantially-constantly-rotating driving-train including a toothed sector-actuating member; an intermittently-rotating driven-member; a spiral energy-storing coupling-spring operatively interconnecting the said driving-train with the said driven-member for effecting the movement of the latter by the said driving-train; a stop-abutment; a toothed sector pivotally carried by the said intermittently-rotating driven-member and engaged with the teeth of the toothed member of the said driving-train; a rotary latch-member carried by the said driven-member and operatively connected to the

said toothed sector for being turned thereby out of engagement with the said stop-abutment to release the said driven-member for rapid movement by the said spiral coupling-spring; and automatic positive-coupling means acting to cause the said toothed sector-actuating member of the said driving-train to positively drive the said driven-member when the said spiral coupling-spring fails to function.

5. A rotary-motion translating-device, including in combination: a substantially-constantly-rotating driving-train including a toothed member; an intermittently-rotating driven-member; resilient coupling-means operatively interconnecting the said driving-train with the said driven-member for effecting the movement of the latter by the said driving-train; a stop-abutment; a toothed sector pivotally carried by the said intermittently-rotating driven-member and engaged with the teeth of the toothed member of the said driving-train; a latch-member carried by the said driven-member and operatively connected to the said toothed sector for being moved thereby out of engagement with the said stop-abutment to release the said driven-member for rapid movement by the said resilient coupling-means; and a driving-abutment carried by the said toothed sector and engageable with the said rotary toothed member of the said driving-train to cause the said driving-train to positively drive the said driven-member when the said resilient coupling-means fails to function.

6. A rotary-motion translating-device, including in combination: a substantially-constantly-rotating driving-train including a toothed member; an intermittently-rotating driven-member; a spiral energy-storing coupling-spring operatively interconnecting the said driving-train with the said driven-member for effecting the movement of the latter by the said driving-train; a stop-abutment; a toothed sector pivotally carried by the said intermittently-rotating driven-member and engaged with the teeth of the toothed member of the said driving-train; a latch-member carried by the said driven-member and operatively connected to the said toothed sector for being moved thereby out of engagement with the said stop-abutment to release the said driven-member for rapid movement by the said spiral energy-storing coupling-spring; and a driving-abutment carried by the said latch-sector and engageable with the said rotary toothed member of the said driving-train to cause the said driving-train to positively drive the said driven-member when the said spiral coupling-spring fails to function.

ARTHUR B. POOLE.
